UNITED STATES PATENT OFFICE.

JOHN FRY, OF PORTLAND, OREGON.

TRAFFIC SIGNAL.

1,405,997.

Specification of Letters Patent. Patented Feb. 7, 1922.

Application filed January 29, 1921. Serial No. 440,998.

To all whom it may concern:

Be it known that I, JOHN FRY, a subject of the King of England, and residing at Portland, in the county of Multnomah and

5 State of Oregon, have invented certain new and useful Improvements in Traffic Signals, of which the following is a specification.

The purpose of the present invention is to provide a traffic signal including a tail light, 10 the construction and arrangement of the housing therefor being such as to include a license number housing, into which the light from the lamp shines, in order to disclose the license number.

15 Another purpose is to provide a device of this character, including a single housing or frame having two lateral moving signal arms and a license number housing, the main housing having a red bull's eye glass, where- 20 by a single electric lamp mounted in the main part of the housing, will illuminate the entire interior of the housing, as well as the arms and the license number housing.

Still another purpose is to provide a signal 25 including a housing with its exterior of some suitable dark color, preferably green or the like, and its interior of white enamel, so as to reflect the ray from the single light, thereby causing the license number to be dis- 30 played, as well as the indicating arrows.

A further purpose is to provide a signal of this kind including a housing movable arms, which are disposed as returning normally forward, in combination with depressible means connected to each arm for moving the same rearwardly, so that when it is limited in its movement, it will assume a position laterally from the main part of the housing or casing, the interior of the arm 35 40 being white enamel, so as to reflect the rays of the light, and indicate the arrow shaped opening.

A still further purpose is the provision of means of electrical character, to operate 45 when the arms are actuated, so as to indicate to the chauffeur or driver of the automobile that the signal has properly operated.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be hereinafter set forth, shown in the drawings and claimed.

60 In the drawings:

Figure 1 is a plan view of a portion of an automobile, showing the improved signal apparatus as applied.

Figure 2 is a rear view of the signal.

Figure 3 is a sectional view on line 3—3 of Figure 2, showing the interior of the housing, and illustrating the single lamp of the main part of the housing and the movable arms thereof.

70 Figure 4 is a detail view of the operating means for the signal.

Figure 5 is a cross sectional view through the license number housing and a portion of the body housing.

75 Figure 6 is a cross sectional view through one of the signal arms.

Referring to the drawings, 1 designates a portion of the frame or body of an automobile, and 2 denotes the housing at the rear 80 of the body, constituting the main portion of a signal apparatus. The signal apparatus is particularly constructed and designed, so that it also includes the signaling arms, as well as the license number section 85 of the housing.

The main portion of the housing may be any suitable shape or configuration, preferably of the contour shown. The main body of the housing at opposite points is provided 90 with spaced ears 3, between which the arm housings 4 and 5 are pivotally mounted as at 6. It will be noted that the opposite portions of the wall of the housing 2 as well as the adjacent ends of the arm housings have 95 a continuous unobstructive passage, so that a single electric lamp may be used in the main body of the housing, to reflect or light upon the enameled interiors 7 of the signaling arms 4 and 5, the exteriors of which are 100 of a solid dark color such as green or the like, in combination with the front walls of the arm housings punched out arrow shape, so that the light may appear therethrough, and reflect the arrow rearwardly.

105 The rear wall of the main body of the housing has a signal opening 8, in which a red glass bull's eye 9 is mounted. The red glass bull's eye will cause the disclosing of red light rays at the rear of the automobile, 110 thereby constituting a tail light. The main body of the housing has a laterally arranged

housing 10 which communicates with the interior of the housing 1. The front wall of the housing 10 is provided with punched out openings 11, which are in the shape of numerals, arranged to make up a license number. In this way the single light in the main body of the signal is used to light up the license number housing, as well as the signal arms, particularly when they are 10 moved in their inoperative vertical position.

Arms 12 and 13 are movable with the pivot 6 of the signal arms, and connected to the arms 12 and 13 are links 14. These links 14 extend forwardly of the body of 15 the automobile and are connected to the angle levers 15, which are pivoted at 16, to the body or frame of the machine. Plunger rods 17 are mounted in guides 18 in the front part of the automobile, in fact adjacent 20 the foot board thereof. Each of these plungers 17 is pivotally connected at 19 to one of the arms of the bell crank levers 15. The push plungers 17 are under tension of the springs 19^a, in order to insure the 25 turning of the plungers to their initial positions. Adjacent where the arms 4 and 5 are pivoted to the main body of the housing, opposite openings are formed in the housing. The adjacent pivoted ends of the arms 4 and 30 5 are open as indicated at 20, to register with the opposite openings 21 of the main body of the housing, whereby the single electric lamp may light up the entire interior of the main body of the housing and the interiors 35 of the arms. The outer ends of the arms 4 and 5 are closed. The walls 22 of the arms 4 and 5 have arrow shaped openings 23, through which the rays from the single lamp reflect or shine, in order to disclose an arrow 40 shaped light. The interiors of the arms 4 and 5 are enameled, in order to insure a very bright reflection of the light rays. The interior of the main body of the housing has 45 its surface white enameled, in order to insure a bright reflection of the light rays.

The main body of the housing has a projection 23^a, to which the coiled springs 24 are connected. These springs are in turn connected to the arm housings 4 and 5, so as 50 to hold them in positions extending normally forward. When the arms 4 and 5 are in their normal positions, the openings or communications between the arms and the main body of the housing are closed, therefore 55 there is no reflection of the light rays into the interiors of the arms 4 and 5. By means of the white enameled inner surfaces of the arms 4 and 5, a white reflection appears through the arrow shaped openings 60 of the arms in the day time, while the light rays will produce the same reflection at night. As previously stated the arms 4 and 5 extend normally forward, and there are two push plungers for operating the arms, 65 one for the arm 4, and another for the arm

5. It will be noted that the arm 4 is designed to be moved to a lateral position, to indicate a turn to the right, while the arm 5 may be positioned laterally to direct movement of the automobile to the left. Hence 70 when it is desired to give directions that it is the intenton of the chauffeur to turn to the right, the right push plunger may be depressed, in which case the pulling action will be imparted upon the link 14, through 75 the medium of the bell crank lever 15. The arm 12 of the housing arm 4 may be moved to a position as shown in Figure 2. When it is desired to turn to the left, the opposite 80 push plunger may be actuated, which will impart a pulling action upon the other link 14, which will rock the arm 13, and move the housing arm 5 to a lateral position, indicating a turn to the left.

A single electric lamp 25 is mounted on 85 the interior of the main body of the housing, and may receive a current supply from any suitable source.

The main body of the housing is provided with a pair of push buttons 26, which are so 90 arranged on the main body of the housing with respect to the arms 12 and 13, that when either of the arms 12 and 13 is moved for moving the signal housings to lateral positions, the arms 12 and 13 will contact with 95 the buttons and close an electric circuit on the wires or leads 27. These wires or leads 27 extend to an electric lamp 28 adjacent the instrument board of the automobile. When these electric lamps 28 are illuminated, the chauffeur or driver is notified that 100 the single arms are properly operative. In other words the chauffeur is notified that one or the other of the housing arms is extended in a lateral position.

The connecting links 14 are provided with safety spring connections, to prevent the overstrain on the operating parts.

The invention having been set forth, what is claimed as being useful is:

In a traffic signal, a main body housing provided with a bull's eye taillight red lens facing rearwardly and having its interior enameled white, the opposite sides of the main body housing having openings, ears 115 projecting from the sides of the main body housing above and below the openings, arm housings pivotally mounted on opposite sides of the main body housing between said ears, certain side walls of the arm housings adapted to close the opening in the opposite sides of the main body housing when the arm housings extend in parallelism forwardly, the opposite side walls of the arm housings provided with punched out arrow 120 shaped openings, said arm housings having their interiors enameled white and having their adjacent pivoted ends open to register with the openings in the opposite sides of the main body housing, whereby an illumination 125

on the interior of the main body housing may be reflected into the arm housings, when one or the other of the arm housings are disposed laterally, whereby their arrow shaped openings may face rearwardly, tensioning means for holding the arm housings in positions extending forwardly, levers carried by the pivots of the arm housings, and means having rod connections with the levers for moving the arm housings to assume lateral positions against the action of the tensioning means.

In testimony whereof I hereunto affix my signature.

JOHN FRY.
